(57) **CLAIM**

The ornamental design for a display screen with animated graphical user interface, as shown and described.

DESCRIPTION

FIG. 1 is front view of a first image in a sequence of a display screen with animated graphical user interface, showing our new design;

FIG. 2 is a front view of a second image in a sequence of a display screen with animated graphical user interface, showing our new design;

FIG. 3 is a front view of a third image in a sequence of a display screen with animated graphical user interface, showing our new design; and,

FIG. 4 is a front view of a fourth image in a sequence of a display screen with animated graphical user interface, showing our new design.

The appearance of the transitional image sequentially transitions between the images shown in FIGS. 1-4. The process or period in which one image transitions to another image forms no part of the claimed design.

The broken line characters and text shown in the figures form no part of the claimed design. The outermost broken lines shown in the figures illustrate a display screen and form no part of the claimed design.
